UNITED STATES PATENT OFFICE.

CHARLES H. DAVIS, OF NEW YORK, N. Y.

ELECTRIC RAILWAY.

SPECIFICATION forming part of Letters Patent No. 605,663, dated June 14, 1898.

Application filed November 2, 1897. Serial No. 657,167. (No model.)

To all whom it may concern:

Be it known that I, CHARLES H. DAVIS, of the city, county, and State of New York, have invented a new and useful Improvement in 5 Electric Railways, of which the following is a specification.

The object of my invention is to make it possible to operate with safety electric-railway trains running at high speeds and short 10 headway.

The invention is here shown embodied in an electric railway having a track and a third rail, wherein the third rail is composed of insulated divisions with which contact is made 15 by the moving vehicle or train successively, circuit being established with the track through the train-motor. The electrical connections are such and their control is such that both the division of the third rail with 20 which the train is making contact and the division immediately in advance thereof are live; but in rear of the train there are always one or more divisions which are dead.

My invention further consists in an electric railway as described in the preceding 25 paragraph, having beside it a series of signal-stations. The relation of the signal system to the divided third rail is such that following a given train there are always one or more 30 divisions on which there is no current and also two or more set danger-signals separated by intervals of one division each.

In the accompanying drawings, Figures 1 to 5 are diagrams illustrating my invention, 35 showing symbolically the relative position and relation of the signals, the trains, and the live and dead divisions of the third rail. Fig. 6 shows a signal-station in elevation, a vehicle on the track, and the means for establishing 40 electrical connection between the vehicle and third rail. Fig. 7 is a plan view of the signal and electrical connections with the insulated sections E F of the third rail. Fig. 8 is a cross-section of the box on the signal-pole, showing the electrical connections 45 therein for conveying the current from the feeder L to the rail-sections. Fig. 9 is an electrical diagram showing the connections between the feeder-line and the signals and 50 the third rail and also the interlocking mechanism. Fig. 10 is an elevation of the four-

armed signal, showing a simple mode of operating the same by hand.

Similar letters and numbers of reference indicate like parts.

55

A B represent the track.

C D represent the third rail, which may be considered as divided into block-sections, one of which, X, is included between the lines x y. A part of the succeeding section is 60 shown at Y. Each section is divided into four subsections, as E F, G H, and I J. The length of each subsection is to be such as that a train running at maximum speed and minimum headway may be brought to a stop by 65 its brakes or other means provided for the purpose within that length. At the boundaries of the sections and subsections are placed signal-stations, of which I here show seven, numbered, consecutively, "1" to "7," 70 inclusive.

At each station there is a safety-signal and a danger-signal. These may be the ordinary semaphore-arms, colored red for "danger" and white for "safety." The red signal, as usual 75 when displayed, indicates that the subsection ahead is blocked; the white signal that said subsection is open. The construction of each signal device at each station is to be such that the danger and safety signals cannot be 80 displayed in predetermined position—as, for example, near the track—at the same time, and also such that the danger-signal must be displayed as many times less one as there are subsections in a section before a safety-signal 85 can be shown—that is to say, if, as here represented, there are four subsections in each section then the danger-signal must be displayed three times before the safety-signal can be displayed once. One way of accomplishing this is illustrated in the accompanying diagram. Four radial semaphore-arms s d d' d'' may be rotated by any suitable means to bring any one arm in predetermined 90 display position—say horizontally—near the track. Obviously only one arm can thus be shown at a time. The four-armed semaphore may also be arranged so that it can be turned in only one direction—say from left to right—as indicated by the curved arrow. Obviously, then, after the arm s has been once 95 displayed it cannot again be shown until the 100

three arms d d' d^2 have been successively exhibited. It is to be understood that I do not limit myself to this particular arrangement of semaphore-arms, which is here merely 5 illustrative.

The signal device at every station and the three signal devices next adjacent thereto are connected together by any known interlocking mechanism, electrical or mechanical, 10 which is constructed so that the safety-arm s cannot be displayed unless a danger-arm d d' d^2 of the other associated signal-stations is simultaneously shown. Thus the signal 7, Fig. 2, is connected by the interlocking devices, as indicated, by the line b to signal 6, by the line c to signal 5, and by the line h to signal 4. Similarly the signal 6 is connected by the interlocking devices, as indicated, by the line e to signal 5, by the line f to signal 4, and by the line g to signal 3. The same is 15 true for all the other signals, the connecting-lines being omitted in the diagram to avoid complication.

In Figs. 1 to 5, U T N represent trains following each other upon the line. U^2 U^3 U^4 represent successive positions of the train U . T^2 T^3 T^4 T^5 represent successive positions of the train T .

Considering Fig. 1, it will be seen that the 20 arm s of signal 5 is displayed and that simultaneously the danger-arms d d' d^2 of signals 2, 3, and 4 are also displayed.

T , Fig. 1, represents a train proceeding in the direction of the arrow. The signal 1 is 25 set at "safety." The operation of the system is then as follows: Train T passes signal 1 and comes upon subsection E, as shown at T^2 in Fig. 2. Signal 1 now turns ahead to exhibit danger-arm d^2 , and signal 2 shows its safety-arm s . The train advances to position T^3 on 30 subsection F, Fig. 3. Signals 1 and 2 exhibit their danger-arms d' and d^2 and signal 3 its safety-arm s . The train advances to position T^4 on subsection G, Fig. 4. Signal 4 can now 35 be set to exhibit its safety-arm s , because signals 1, 2, and 3 each exhibit a danger-arm d d' d^2 . The train advances to position T^5 on subsection H, Fig. 5. Signal 5 can now be set 40 at "safety," because signals 4 3 2 all exhibit their danger-arms, and as there are three danger-signals exhibited in rear of signal 5 signal 45 1 can be set at "safety" to allow a following train N , Fig. 5, to come upon the line. The result, therefore, is that as any given train 50 advances danger-signals are set in three subsections ahead of it and danger-signals set in three subsections behind it. The safety-signal at 55 5 cannot be set to let the train T^5 pass from section X to section Y until three signals 60 4 3 2 all show "danger." The safety-signal at 1 cannot be set to let the train N pass upon section X unless the three signals in rear of 1 all show "danger." A train in advance 65 cannot leave the last subsection of a block-section X until the danger-signals are set in the three following subsections, and a following train cannot come upon that block-section

until the preceding train leaves it nor without setting danger-signals in the three subsections in rear of it.

The third rail CD is physically divided into the subsections E F G H, &c., which subsections are insulated from one another.

L is the feeder-line from the source of current, which communicates by branches m to the several signal-stations. Circuit is closed through the motor of train T from any subsection, as E F G, which is live, with the track by any convenient contact device, such as a brush or wiper M , bearing upon said third rail.

The relation of the branch feeders m to the rail-sections and the signal devices is such that when any signal is set at "danger" circuit is broken from branch to rail, but when any signal is set at "safety" circuit is made from a branch feeder to the two subsections of rail immediately adjacent to the signal-station. I have indicated this in the diagram by showing a circuit-closing spring O on arm s . Thus in Fig. 2, signal 2, the spring O bears on rail-sections F E. Of course this is merely symbolical and shows the relations and not the actual constructions of parts.

Referring now to Fig. 2, the train T^2 is on subsection E, which is live, and because signal 2 is at "safety" it can pass to subsection F, which is also live; but subsection G is not live, so that even if the danger-signal at 3 should be disregarded the train could go no farther than its momentum would carry it upon subsection G, for there it would get no current, and this would be true of subsection H. If, however, signal 3 be set at "safety" when the train comes on subsection F, (T^3 , Fig. 3,) then subsections F and G become live and subsection E is cut out. Thus it will be seen that as a train comes up to a signal, if that signal be at "safety," the subsections on both sides thereof are live; but in advance of these two live sections there are two dead subsections, and in rear of these two live sections are two dead subsections. The full protection afforded by my system to the moving train can now be recognized as follows: Following the train (T^4 , Fig. 4,) so to speak, there are always two subsections of third rail whereon there is no current and also three danger-signals with intervals of a subsection between. The capacity of a given railway-line, as here illustrated, in number of trains therefore depends upon four times the length in which a train can be stopped without danger to the passengers, and this capacity will of course vary with the number of subsections provided in each section.

Referring now to Figs. 6, 7, 8, and 9, I therein show certain specific means for carrying my invention (symbolically illustrated in Figs. 1 to 5) into practical effect. In Fig. 6 the four-armed signal is shown with the safety-arm s in display position. T , as before, represents a train or vehicle running on the track B. The driving-motor is shown symbolically at a and receives current from the third rail

c, through the brush *M*, while also communicating with the ground through the trucks and track *B*. In Fig. 7, in which the parts are shown in plan, *E F* are sections of the third rail insulated from each other at *n* and respectively connected by wires *o o* to the contact-brush *p*, which is located in a box *q* on the signal-pole *r*. Upon the shaft *t* of the four-armed signal is a sleeve *u*, having a projecting arm *v*, which when the signal is set, as shown, with the safety-arm *s* displayed makes electrical contact with the contact-brush *p*. Also in the box *q* and bearing on the sleeve *u* is a spring *w*, which connects by wire *m* with the feeder *L*. When the signal is set as represented, circuit is therefore closed from feeder *L* by wire *m* to sleeve *u*, arm *s*, brush *p*, and wires *o* to the third-rail sections *E F*. In this way I practically produce the result referred to illustratively in Figs. 1 to 5 as caused by the circuit-closing spring *o*.

The interlocking mechanism connecting the several signals is illustrated in electrical diagram in Fig. 9, which also shows the branch feeders *m* connecting the signals with the main feeder *L* and the wires *o* as connecting the signals with the sections of the third rail, as already described.

Referring to Fig. 7, the signal-arms *d' d²*, &c., are mounted on a shaft which is journaled in the box *q*, which shaft carries a barrel *a'*, from the periphery of which projects pins, one of which is shown in Fig. 7 at *b'*. Within the box *q* are contact-springs, normally separated, but which when the barrel rotates in certain definite positions through the turning of the signal-arms are pressed together by the pins *b'*, thus establishing an electrical circuit from the feeder *L* by way of the wire *c'* through the springs and then by wire *e'* to a return-wire *L'*, which wire may be connected to ground by the wire represented in dotted lines at *g'* in Fig. 9, this wire being here shown as connected to the track.

Referring to Fig. 9, the barrel *a'*, belonging to each signal, as 1 2 3 4, is shown developed opposite that signal, and adjacent to the barrel are shown the contact-springs, before referred to. Thus opposite signal 4 in Fig. 50 9 barrel *a'* is so turned that one contact-pin *b'* closes contact between the springs 8 and 9, while at the same time the springs 10 and 11 are not pressed together. Opposite signal 3 the barrel *a'* is so placed that the springs 12 and 13 and 14 and 15 are pressed together, while the springs 16 and 17 are open. Opposite signal 2 the barrel *a'* is so placed that the springs 18 and 19 and 20 and 21 are pressed together, while the springs 22 and 23 are open. Opposite to signal 1 the barrel *a'* is so placed that the springs 24 and 25 and 26 and 27 are pressed together. These positions of the barrel and these closings and openings of the springs correspond, of course, to the positions of the signals 1 2 3 4 shown in Fig. 9. If the signals should be put in some other position, then the closing and opening of the springs would be

different and correspond to that new position, as will hereinafter be more clearly explained. Also on the shaft of each signal are locking-wheels, as 28 29 30 31. Adapted to engage with these wheels are pivoted dogs 32 33 34 35. Each dog is disposed in front of an electromagnet 36 37 38 39 and forms the armature of that magnet, so that when the magnet is excited the dog is drawn up and out of engagement with the locking-wheel, so that the signal-shaft is then free and may be turned by any suitable means.

In Fig. 9 I have shown a vehicle or train *T⁶* 80 as having just passed the signal 3 and as coming to the signal 4. The signals 1 and 2 have already been set to "danger" in rear of the train, and it is now necessary to set the signal 4 to "safety" to allow the train to pass while setting signal 3 to "danger" in rear of the train. It is obvious that this can be done, because circuit is made from the feeder *L* through the magnet 36 and springs 8 and 9, 12 and 13, 18 and 19, and 24 and 25. The signal 4 is then 90 turned a quarter-turn to the right, bringing the arm *s* into "danger" position. The effect of so turning the signal is to break contact between the springs 8 and 9 and establish contact between the springs 10 and 11. This makes 95 circuit from the feeder *L* through the magnet 37 and springs 10 and 11 and 14 and 15, thus energizing magnet 37, causing it to lift its armature 33, thus freeing the wheel 39, so that signal 3 may then be turned a quarter-turn 100 forward, which is to place it in "danger" position. The effect of turning signal 3 a quarter-turn forward is to establish connection between the springs 16 and 17 and break it between the pairs of springs 12 and 13 and 14 105 and 15. Circuit is then made from the feeder *L* through the magnet 38, springs 16 and 17 and 20 and 21. Therefore magnet 38 is energized, raising the dog 34 and permitting the signal 2 to be turned a quarter-turn in advance, thus keeping that signal at "danger." 110 The turning of signal 2 establishes connection between springs 22 and 23 and breaks it between springs 20 and 21. Circuit is then made from feeder *L* through the magnet 39, 115 springs 22 and 23 and 26 and 27, thus allowing signal 1 to be turned a quarter-turn ahead, which will result in still keeping that signal 120 so as to display "danger." This brings signal 1 into position, so that its next movement forward will be to display the safety-arm.

The operation of this interlocking mechanism is fully set forth in another application for Letters Patent, Serial No. 664,195, filed by me December 29, 1897, and therefore said mechanism is not herein specifically claimed.

In order to prevent large expenditure of current through the interlocking devices, I introduce into the wires *c'* suitable resistances, (indicated at *h'*.)

In lieu of dividing the third rail into insulated sections I may divide an insulated track into insulated sections and make contact with a grounded continuous third rail.

The term "line" as used in the claims means either a track and a third rail divided into insulated sections, as described, or an insulated track divided into insulated sections and a continuous grounded third rail or any equivalent arrangement.

The four-armed signal may be operated by hand in the manner hereinbefore set out by means of the following simple mechanism:

- 10 On the shaft of the arms d d^2 , &c., is a sprocket-wheel A^2 , and on the signal-post E^2 there is a similar sprocket-wheel B^2 . A chain belt C^2 passes over both of these sprocket-wheels. By rotating the sprocket-wheel B^2 by 15 means of the crank D^2 the signal-arms may be rotated and adjusted as described.

I claim—

1. In an electrical railway a line divided into insulated divisions, signal devices respectively located between the successive divisions, means for actuating said signal devices successively to give a definite indication, and means controlled by each signal device for then establishing electrical circuit in 25 the line-divisions between which it is located, substantially as described.

2. In an electrical railway, a line divided into insulated divisions, signal devices respectively located between successive divisions, each device being constructed to exhibit a danger-signal and a safety-signal, and means controlled by each signal device for establishing current in the two line-divisions between which said device is located, when 35 the safety-signal of that device is exhibited, substantially as described.

3. In an electrical railway a line divided into insulated divisions, a signal device associated with each division and constructed to exhibit a danger-signal and a safety-signal, and means controlled by said signal device for interrupting electrical circuit through the associated line-division when the danger-signal of that device is exhibited, substantially as described. 40

4. In an electrical railway, a line divided into insulated sections, each section having two or more insulated subsections, signal-stations located at the boundaries of said sections and subsections, a signal apparatus located at each substation and constructed (1) to exhibit a danger-signal and a safety-signal (2) to show said danger-signal successively as many times less one as there are substations in each section before said safety-signal can be displayed (3) to establish current in the two subsections between which said apparatus is located when said safety-signal is displayed, and interlocking devices connecting said signal-station with as many 50 signal-stations next adjacent thereto as equal in number the number of subsections less one; the said interlocking devices being constructed and operating so that the safety-signal of one station cannot be displayed until the danger-signals of the aforesaid adjacent signal-stations are first shown, substantially as described. 55
